UNITED STATES PATENT OFFICE.

GUSTAF M. WESTMAN, OF NEW YORK, N. Y.

STEAM OR GAS TURBINE.

SPECIFICATION forming part of Letters Patent No. 595,748, dated December 21, 1897.

Application filed April 18, 1896. Renewed February 18, 1897. Serial No. 624,079. (No model.)

To all whom it may concern:

Be it known that I, GUSTAF M. WESTMAN, of New York city, in the county and State of New York, have invented a new and Improved 5 Steam or Gas Turbine, of which the following is a full, clear, and exact description.

The object of the invention is to provide a new and improved steam or gas turbine which is simple and durable in construction and arranged to use the steam or compressed gas expansively, to insure a full utilization of the force of the motive agent, and at the same to reduce friction and jar incident to the high speed of the turbine to a minimum.

15 The invention is an improvement in the class of turbines in which the motive agent or fluid is discharged tangentially from the periphery of the wheel.

20 The novel construction and combination of parts embodying the invention are as herein-after described and claimed.

Reference is to be had to the accompanying drawings, forming a part of this specification, in which similar characters of reference indicate corresponding parts in all the figures.

25 Figure 1 is a sectional plan view of the improvement on the line 1 1 of Fig. 2. Fig. 2 is a sectional side elevation of the same on the line 2 2 of Fig. 1, and Fig. 3 is a sectional 30 plan view of part of the improvement on the line 3 3 of Fig. 2.

The improved steam and gas turbine is provided with a stationary disk A, the lower portion of which is fitted loosely into a correspondingly-shaped recess formed in the top of the turbine wheel B, disposed horizontally and inclosed within a casing C, having a steam-outlet C' in its bottom, as plainly indicated in Figs. 1 and 2. The turbine wheel 35 B is secured at its hub B² on a main shaft D, set with its lower reduced end D' in a step E, held on a suitable foundation.

40 In the stationary disk A are arranged a series of radially-disposed passages A', increasing in size outwardly and terminating at their inner smaller ends in a central opening A², connected with a supply-pipe F, attached to the top of the disk A and connected with a suitable source of steam or compressed-gas 45 supply. The outer end of each passage A' terminates in a series of channels A³, standing at angles to the passages A' and discharg-

ing the motive agent at their outer ends into the inner ends of buckets B', formed horizontally in the turbine wheel B. The buckets B' are preferably curved, as indicated in Fig. 1, with the inner ends larger than the outer contracted ends, which latter discharge the motive agent approximately tangential to the periphery of the wheel B.

55 The inner ends of the walls of the buckets B' stand approximately at right angles to the walls of the channels A³, so that the motive agent in passing into the buckets presses against the walls thereof, to cause the turbine 60 wheel to rotate in the direction of the arrow a', and the motive agent in discharging at the outer contracted ends of the buckets into the open air gives an additional impulse to the wheel B, so as to rotate the same in the 65 aforesaid direction.

70 Now it will be seen that as the motive agent passes through the passages A' it is free to expand upon reaching and passing into or through the channels A³, so that the full force 75 of the motive agent is utilized at the time the said expanded steam or gas passes into the buckets B' to act thereon, as above mentioned.

75 In order to distribute the motive agent properly to the inner ends of the several passages A', I provide a cone G, the base of which extends below the bottoms of the passages A' within the opening A² and with the apex of said cone extending horizontally in the said opening, so that the steam or gas 80 passing down the pipe F is divided by the cone and distributed to the several passages A'. The cone G is secured within the disk A, and from the base of the cone extends downward a pin G', passing loosely through a large 85 bore in the hub B² of the turbine wheel B. The lower end of this pin G' is rounded off to engage a recess in the upper end of the shaft D, so that an additional bearing is formed for the said shaft D and the turbine 90 wheel B. In order, however, to make a flexible connection between the stationary disk A and the wheel B and its shaft D, I provide a number of blocks H, fitted in recesses in the hub B² and engaging the pin G', said blocks 95 H being pressed inwardly against the said pin G' by springs H', held in apertures formed in the hub B², with the outer ends of the springs resting on screw-plugs H², secured in 100

the hub B². (See Figs. 2 and 3.) A similar flexible connection is made between the reduced end D' and the step E, and for this purpose blocks I are fitted in recesses in the step 5 E to engage the sides of the reduced end D' of the shaft D. The blocks I are pressed on by springs I', resting with their outer ends on plugs I², holding the springs in the recesses in the step E.

10 In order to take up all jars and vibrations incident to the high speed of the turbine wheel and transmit them to the disk A, I provide the pipe F, secured on said disk, with external projections F', resting against a rubber 15 ring J, secured within the neck C², formed on the top of the casing C. It is evident that by the arrangement described a flexible connection is established between the wheel B and the stationary disk A, and at the same 20 time all vibrations and jars in a lateral direction are compensated for by the spring-pressed blocks and rubber ring above mentioned. Thus it is evident that the turbine wheel is at all times self-centering, and consequently 25 very little friction is encountered, and the motive power is utilized to the fullest advantage and transmitted to the machinery to be driven. The rotary motion of the shaft D can be transmitted by gear-wheels K K' to a 30 horizontal shaft K²; but it is evident that other suitable means for transmitting the power may be employed.

Having thus fully described my invention, I claim as new and desire to secure by Letters 35 Patent—

1. A turbine of the class described, comprising a horizontally-disposed turbine wheel provided with buckets discharging the motive agent at their outer ends approximately 40 tangential to the periphery of the wheel, and a stationary disk connected with the motive-

agent supply, and having a series of passages each terminating at its outer end in a series of channels discharging the motive agent to the inner ends of said buckets, said channels 45 standing at angles to the said passages and approximately at right angles to the walls of the buckets, substantially as shown and described.

2. A turbine of the class described, comprising a horizontally-disposed turbine wheel provided with buckets, larger at their inner ends than at their outer, discharge ends, said buckets being arranged to discharge the motive agent approximately tangential to the 50 periphery of the wheel, a stationary disk having a central opening connected with the motive-agent supply, a series of passages leading from said opening, and a series of channels leading from the inner end of each passage at 55 angles thereto, to discharge at their outer ends into the inner ends of said buckets, substantially as shown and described.

3. A turbine of the class described, comprising a horizontally-disposed turbine wheel 65 provided with buckets, larger at their inner ends than at their outer, discharge ends, said buckets being arranged to discharge the motive agent approximately tangential to the periphery of the wheel, a stationary disk having a central opening connected with the motive-agent supply, a series of passages leading from said opening, a series of channels leading from the inner end of each passage at 70 angles thereto, to discharge at their outer ends into the inner ends of said buckets, and a distributing-cone held in said opening, substantially as shown and described.

GUSTAF M. WESTMAN.
